DISPLAY STAND

Arthur R. Botham, New York, N. Y., assignor to
 Coty, Inc., Wilmington, Del., a corporation of
 Delaware

Application February 8, 1934, Serial No. 710,210

7 Claims. (Cl. 211—77)

The present invention relates to new and useful improvements in display devices, and more particularly to a display device for perfumes and the like, and has special reference to a revolving 5 illuminated display stand for perfume bottles.

The invention resides in the features of construction of a stand especially designed to hold sample or show bottles, for example, such bottles containing perfume, in a manner designed to 10 produce a compact, neat and attractive display. The invention is particularly useful in providing means for revolving the bottles for the purpose of rendering any desired bottle easily accessible, together with means for securing the bottles 15 against accidental displacement, means for illuminating the display stand, the bottles and the name plates identifying the maker and the particular perfumes displayed, and in the peculiar arrangement and combinations of these various 20 parts, all as more fully hereinafter set forth.

With these various objects in view, the invention consists essentially in providing a suitable fixed platform having a hollow vertical standard projecting upwardly from the center thereof, said 25 vertical standard being provided with a post light and name plate for the purpose of illuminating and identifying the display. The invention also contemplates a movable platform adapted to revolve about said standard and upon said fixed 30 platform, said movable platform being constructed and arranged to hold a plurality of bottles or other receptacles and a plurality of spring holders associated with said movable platform and terminating in forked pieces adapted 35 to extend around the necks of the bottles for the purpose of holding them in place. The spring holders may be joined at their outward extremities by chains having name plates depending therefrom for the purpose of identifying contents 40 of the various bottles.

In the particular embodiment herein disclosed, there is shown a circular dispensing stand designed for six elliptical bottles, but it is to be understood that the shape of the stand and the 45 shape of the bottles or other receptacles may be varied without departing from the spirit of the invention. Furthermore the invention is not limited to the number of bottles or other receptacles, as the stand may be constructed to display 50 a greater or smaller number of bottles, if desired.

Further objects of the invention will be apparent from the accompanying drawing, in which like reference characters denote like parts, and 55 in which:

Fig. 1 is a top plan view of the display stand partly broken away with the bottles removed;

Fig. 2 is a central vertical section of the stand taken on the line 2—2 of Fig. 1, showing two bottles in place therein; and

Fig. 3 is a side elevation, partially in section, of a portion of the stand.

Referring more particularly to the drawing, 10 designates the movable upper platform revolvable on the fixed lower platform 11 and provided at its central portion with an opening 10' to permit the passage of the fixed standard 15 which is securely mounted upon the fixed platform 11 and immovably secured thereto by means of a lock nut 16. The lower platform 11 has secured 15 to it a plate 12, provided with an annular depression 13, the upper platform being likewise provided with a concentric annular depression 13' of equal diameter, both annular depressions serving for the reception and retention of anti-friction balls 14 which provide rolling bearings upon which the platform 10 revolves, as will be easily understood. The upper platform 10 is provided with a plurality of rings 17, serving to hold the bases of the bottles 25 to be displayed upon 20 the stand in their normal position.

The platform 10 has a glass cylinder 20 mounted thereon in vertical position and encasing the vertical standard 15. A plurality of spring bottle holders 18, are also mounted upon the 25 upper platform 10 at the central portion thereof surrounding the cylinder 20.

The bottle holders 18 are shown as being mounted upon the movable upper platform 10 by means of screws 27 attaching them to an annular upright ring 33 which is fastened by screws 34 to the platform 10 concentrically therewith. Each spring bottle holder 18 is composed of a strip of metal and is curved outwardly above the concentric annular ring 33. The upper ends of the 30 bottle holders 18 are bifurcated, as shown at 19 and the bifurcations 19 extend directly over the rings 17 on the upper platform 10. The height of the bifurcations 19 above the upper platform 10 is such that a bottle 25 with its base contained 35 in the ring 17 beneath the bifurcation will stand with its neck projecting between the bifurcations with the latter pressing upon the shoulders of the bottle. Thus the bottles are yieldably held in place by the bottle holders 18 and the rings 17. 40 Chains 21 may have their ends fastened in the ends of the bifurcations and name plates 22, for the purpose of identifying the contents of the various bottles displayed, may depend from the 45 chains.

115

The hollow vertical upright 15 supports a post light 23 which is encased in the glass cylinder 20, as is the upright 15. A wire connection 29 supplies current to the post light 23, extending 5 through the hollow vertical upright 15 and passing out of the apparatus through a groove in the base of the platform 11. The hollow vertical upright 15 also supports a name plate 24 above the glass cylinder 20.

10 The glass cylinder 20 is fitted with a cover 30 at its upper end, the cover having an opening 31 at its center to permit passage of the vertical standard 15 and a plurality of openings 32, to permit the escape of air heated by the post 15 light 23.

It is preferred to construct the platforms of bakelite or a similar material, and to form the cylinder 20 of frosted glass. The vertical upright, the name plate and the spring holders are preferably of metal having a chromium finish. The lower fixed platform 11 may also be of bakelite and may likewise be decorated with chromium bands. It should be noted, however, that the invention is not restricted to these materials or 25 to this ornamentation.

The invention has been shown only as adapted to a display stand for bottles such as perfume bottles and the like, but it is obvious that many modifications are possible which do not depart 30 from the spirit of the invention. With the understanding that the embodiment here described and illustrated in the drawing is presented not as a limitation but merely to indicate how the invention may be applied.

35 I claim:

1. A display stand for bottles comprising a fixed platform, a platform revoluble upon said fixed platform for supporting a plurality of bottles, and spring holders with ends which have 40 portions to normally engage the shoulders of the bottles on opposite sides of the bottle necks and carried by said revoluble platform for resiliently pressing upon the shoulders of the bottles on either side of their necks toward said revoluble 45 platform to maintain the bottles in position thereupon.

2. A display stand for bottles comprising a fixed platform, a platform revoluble upon said fixed platform for supporting a plurality of bottles, and unitary spring holders having bifurcated ends carried by said revoluble platform for 50 resiliently pressing upon the shoulders of the

bottles on either side of their necks toward said revoluble platform to maintain them in position thereupon.

3. A display stand for bottles comprising a fixed platform, a platform revoluble thereon for supporting a plurality of bottles, spring holders carried by said revoluble platform, said spring holders being adapted to hold and resiliently press downwardly upon said revoluble platform bottles to be displayed to maintain them in a pre-determined position. 80

4. In a display stand for bottles, a movable upper platform, a fixed lower platform, said upper platform being revoluble upon said lower platform, and spring holders for said bottles being bifurcated at their outer ends and curved to resiliently press downwardly upon the shoulders of bottles to hold them upon said upper platform. 90

5. In a display stand for bottles, a movable upper platform, a fixed lower platform, concentric opposed grooves of equal diameter in said two platforms, antifriction balls in said grooves for supporting said upper platform revolably upon said lower platform, spring holders with 100 ends adapted to engage the bottles on opposite sides of the necks of the bottles and carried by said upper platform, said spring holders being adapted to hold and exert a resilient pressure upon said bottles to be displayed by pressing upon 105 the shoulders of said bottles in a direction toward said upper platform.

6. A display stand for bottles comprising a fixed platform, a platform revoluble upon said fixed platform for supporting a plurality of bottles, unitary spring holders having bifurcated ends carried by said revoluble platform and adapted to exert a resilient pressure upon the shoulders of the bottles on either side of their necks to maintain them in position upon said 110 revoluble platform, and a releasable joining member between said bifurcations. 115

7. In a display stand for bottles, a movable upper platform, a fixed lower platform, said upper platform being revoluble upon said lower platform, unitary spring bottle holders mounted upon said upper platform, said spring holders being bifurcated at their outer ends and curved to exert a resilient pressure upon the shoulders of the bottles to hold them upon said 120 upper platform. 125

ARTHUR R. BOTHAM.
